POWER TUBE

Irvin W. Cox, West Allis, and Lester D. Drugmand, Milwaukee, Wis., assignors to Cutler-Hammer, Inc., Milwaukee, Wis., a corporation of Delaware

Application January 30, 1946, Serial No. 644,270

21 Claims. (Cl. 250—27.5)

1

This invention relates to improvements in power tubes, and the invention relates more particularly to a tube embodying a pool type cathode.

The purpose of this invention is to provide a reliable starter, of exceedingly long life (of more than one hundred times the life of the well known band-type starter), for a power tube of the reconstructible cathode type, which tube will operate not only for conduction of relatively large values of energy, but also for conduction of relatively small values of energy comparable to the values required to influence the discharge of a hot cathode type of tube having grid control, such as a "Thyratron." An essential feature of the starter herein contemplated is the provision of a substantially unidirectional stream or jet of vapor of the same material as that of which the pool type cathode is formed, which jet is ionized only at the instant at which it is desired to start conduction in the tube. The timing of the ionizing pulse is accomplished by means of an appropriate phase control circuit, and the jet is directed toward the reconstructible cathode (usually a mercury cathode) so that when the jet is ionized it starts an arc spot at the point where it impinges upon the cathode surface and at the instant of ionization. The starting of this arc spot in accordance with our invention is very rapid, and very reliable, and its 60 cycle production, as an average, requires less than one watt of 60 cycle ionizing energy.

The following are some of the advantages of such a starter:

1. The source of the ionized vapor is reconstructible and hence indestructible. The ionizing agent is a unidirectional gas stream and is unaffected by relatively large variations in the height or level of the cathode pool, inasmuch as the vapor of the jet is traveling at the enormous molecular velocity associated with its temperature.

2. The ionizing or igniting agent is itself of the nature of an arc at the instant it impinges upon the surface of the cathode, and we have found in practice that it will start an arc from the cathode to the anode within a time period of the order of a microsecond.

3. Inasmuch as the average wattage necessary for the ionization at 60 cycles is less than one watt, deterioration of the starter elements (herefore always associated with high energy concentration) cannot take place, and long life for the starter (and consequently for the tube as a whole) is thus insured.

4. The low wattage necessary for the starting

2

means decreases the total amount of energy which must be dissipated by the cooling means (when employed), so that a tube with limited cooling means may be rated as much as twenty-five per cent higher, when using a starter of the character herein disclosed, as compared with a similar tube employing the usual igniter rod. For example, a 16 kilowatt tube (in a 440 volt, 60 cycle alternating current circuit) having a cooling system just sufficient when using an igniter rod, may be rated as a 20 kilowatt tube (with the same cooling system) when the starter herein disclosed is employed; and the same amount of heat will be carried away.

5. Of very great importance is the fact that the demand energies are so much lower for the starter herein disclosed than for the conventional form of igniter rod starter that even the smallest of the "Thyratron" type of tubes are more than adequate for its control. The control unit for the tube herein disclosed may be compact and inexpensive, and make small demand in respect of power consumed, while minimizing the amount of heat generated in the control cabinet. The starter herein disclosed is so reliable that proper operation of the tube is insured even though the current passing therethrough is varied from a value of hundreds of amperes down to a value of a few milliamperes, by means of phase control, without any other change in the circuit. For example, a continuous decrease in current from a relatively high value to a value lower than 5 milliamperes may be effected with a tube of the character herein contemplated.

35. A primary object of the invention is to provide a novel form of starting means for such tubes which is more rapid and hence more reliable than starting means heretofore proposed.

Another and more specific object is to provide for use of an ionized vapor jet as the starting medium for the tube.

Another object is to provide for generation of the vapor of the jet from a body of material like that of the cathode but arranged in electrically insulated relationship to the latter.

Another object is to provide an electrically insulated boiler for the separate body of cathode material having associated therewith an auxiliary electrode whereby the generated vapor may be substantially instantaneously ionized at will.

Another object is to provide for impingement of at least a portion of the ionized vapor of the jet against a dielectric element at a point closely adjacent the point of impingement of said jet 55 against the cathode surface.

Another object is to provide a source of ionized vapor which is reconstructible and hence indestructible.

Another object is to provide an ionizing agent traveling at a very high molecular velocity corresponding to its temperature, whereby the same is functionally effective regardless of relatively large changes in the level of the cathode pool.

Another object is to provide an ionized igniting agent which is itself of the nature of an arc at the instant it impinges upon the cathode surface, whereby the time required to start an arc from the cathode to the anode is minimized.

Another object is to minimize the wattage necessary for ionization of the igniting agent to correspondingly increase the effective life of the tube.

Another object is to utilize such minimized wattage to afford a substantially increased rating of the tube.

Another object is to provide a tube of the aforementioned character wherein the starter is so reliable that the value of current transmitted by the tube may be varied from hundreds of amperes to a few milliamperes by means of phase control without any other change in the circuit.

Other objects and advantages of the invention will hereinafter appear.

The accompanying drawings illustrate certain embodiments of the invention which will now be described; it being understood that the invention is susceptible of embodiment in other forms within the scope of the appended claims.

In the drawings:

Figure 1 is a vertical sectional view of a power tube having our improved starting means incorporated therein.

Fig. 2 is a fragmentary side elevational view of certain elements of the tube shown in Fig. 1.

Fig. 3 is a sectional view, on the line 3—3 of Fig. 1.

Fig. 4 is an enlarged fragmentary sectional view of an arrangement of parts similar to that shown in Fig. 1, but illustrating a modification wherein portions of the ionized vapor jet are adapted to substantially simultaneously impinge against a dielectric element and the surface of the cathode.

Fig. 5 is a fragmentary elevational view of certain of the elements shown in Fig. 4; the normal level of the cathode pool being indicated by the dotted line.

Fig. 6 is a fragmentary view similar to Fig. 5, but showing a modified form of dielectric means against which the vapor jet is adapted to impinge, and

Fig. 7 is a fragmentary sectional view of a device similar to that shown in Figs. 1 to 3, but with the upper end of the hood or dome omitted and with the bell of the boiler attached at a plurality of points to the overflow weir for support of the former.

Referring first to Figs. 1 to 3, the numeral 10 designates an evacuated and sealed tube or flask, which is here shown as composed of glass of suitable composition. The main body of tube 10 is preferably of substantially circular form in transverse cross section throughout the major portion of its length. Tube 10 is provided at its upper end with a downwardly and inwardly convergent annular flange 11 having the relatively thicker top portion 12 formed integrally therewith. Portion 12 is formed as shown at 13 to afford a glass to metal seal with respect to intermediate portion 14^a of an anode lead whose

upper and lower portions are designated by numerals 14 and 14^b. The section 14^a is composed of a metal, such as tungsten, suitable for co-operation with the glass seal 13, and sections 14^a and 14^b may be composed of any other metal or metals suitable for their respective purposes, and united with portion 14^a, as by welding. Portion 14^b is welded or otherwise rigidly connected mechanically and electrically to the anode 15, which may consist of a ring or tube section composed of iron. Although I have shown only one anode lead 14, 14^a, 14^b, it is to be understood that in practice two or three of such leads will ordinarily be employed.

Numeral 16 designates the upper portion of a cathode lead; the same being united with one end of an intermediate portion 16^a which is surrounded by a glass seal 13^a. Attached to the lower end of portion 16^a is a relatively long portion 16^b whose lower end is immersed in the mercury pool 17 which forms the reconstructible cathode of the tube. In practice said portion 16^b has its lower end bent at substantially a right angle thereto, as indicated at 16^c to form a supporting shoulder for the lower end of a glass tube 18, whose upper end surrounds and is fused or sealed to the hollow tubular extension 13^b of the glass seal 13^a. By this means the portion 16^b of the cathode lead is properly insulated from the anode 15, while providing for circuit connection of both the anode and the cathode at the upper end of the tube. If desired, one or more additional cathode leads 16, 16^a, 16^b, 16^c, each having a glass tube 18 associated therewith, may be employed in the power tube 10.

The top portion 12 of tube 10 has a tubular member 19 rigidly attached to and communicating with the interior thereof to provide for exhausting the interior of tube 10 to the desired degree, as by means of a suitable vacuum pump (not shown). After creation of the desired degree of vacuum within tube 10, member 19 is fused at a given point to provide a seal or closure 19^a.

The portion 10^a of tube 10 which supports the mercury pool 17 is preferably of substantially reduced diameter, as shown.

Our novel starting means for tube 10 is mounted at the lower end thereof in proper relationship to the cathode pool 17. Said means as shown comprises a glass hood or dome 20 whose lower edge 20^a is fused to seal the same to the peripheral edge of an opening formed in the bottom wall 10^b of tube 10. Hood 20 is provided in its peripheral wall with an opening 20^b, here shown (Fig. 2) as of substantially rectangular contour; the lower edge of opening 20^b acting as a weir to provide for overflow of the mercury of pool 17 when the same rises above a predetermined level. Opening 20^b also provides for outward flow or projection of a jet of mercury vapor into contact with the surface of cathode pool 17, in the manner illustrated and herein-after described.

Hood 20 has fused thereto at 21^a (for support thereby) a glass bell 21 having a relatively long downward tubular extension 21^b, to the lower end of which an upwardly extending tubular glass member 21^c is rigidly united, as by fusion, at the point 21^d. Member 21^c extends substantially throughout the length of extension 21^b, and has its upper peripheral edge bent inwardly toward, but out of sealing contact with, said extension 21^b; the member 21^c being peripherally spaced

outwardly from extension 21^b to provide a heat insulating spaced therebetween.

Fused to the lower surface 10^a of tube 10, in alignment and in communication with hood 20, is a glass chamber member 22; the latter having a reentrant tubular portion 22^a formed centrally thereof to extend upwardly throughout the length of extension 21^b and into the aforementioned bell 21; the closed upper end of portion 22^a being designated by numeral 22^b.

The aforementioned member 21^c is preferably provided at vertically spaced points with sets of three or more outwardly projecting bosses (shown as of hollow formation, and designated by numerals 21^c and 21^d, respectively). Said bosses 21^c and 21^d are accommodated within, but are closely adjacent to the peripheral inner surface of chamber 22 to stabilize and insure positioning of the extension 21^b and member 21^c within chamber 22. Bell 21 has a relatively small opening 21^e formed therein and angled downwardly, as shown in Fig. 1 to provide for passage of the vapor jet or stream therethrough and through the opening 20^b for impingement thereof against the surface of cathode 17.

Positioned within the reentrant tubular portion 22^a is an electric heating element of any suitable form. The heating element is shown as comprising a cylindrical core or rod 23 formed of porcelain or similar ceramic material, upon the exterior of which is coiled a flat strip 24 of suitable resistance material; as, for instance, a strip composed of an alloy of nickel and chromium, the coils of the strip being substantially spaced from each other as illustrated. A wire lead 25 is welded, brazed, or otherwise electrically connected to the lower end coil of strip 24, and a wire lead 26 is similarly connected to the upper end coil; core 23 having a through passage formed therein to accommodate lead 26 and to insulate the same from all but said upper end coil.

Leads 25 and 26 are adapted to be connected in circuit with any suitable source of energy supply (not shown). In practice electric current is supplied to the strip 24 of resistance material a short time before it is desired to start tube 10 in operation, and the heater then remains in circuit throughout the operation of the power tube.

Chamber 22 as shown is adapted to contain a body of mercury 17^a which is normally electrically and mechanically insulated or separated from the cathode 17. We prefer to provide the chamber 22 with an outward annular bulge or recess 22^c to increase the surface area of the mercury body 17^a at or adjacent the normal level thereof within chamber 22. Prior to completion of the heater circuit it will be apparent that the mercury of body 17^a will extend upwardly in a thin annular or tubular shape 17^b between the outer surface of reentrant tubular portion 22^a and the inner surface of the aforementioned downward extension 21^b to approximately the same level as that portion of mercury body 17^a between chamber 22 and the outer surface of member 21^c. Upon completion of the heater circuit the portion 17^b of mercury body 17^a will be rapidly heated to a temperature such as to cause generation of mercury vapor, which is released at the upper surface thereof and flows upwardly into the bell 21, as indicated at 17^c; such vapor being further heated during its upward flow.

The vapor is permitted to escape through the opening 21^e aforementioned, and upon development of sufficient pressure the vapor will be

ejected in the form of a jet 17^d which is adapted to impinge against the surface of the mercury pool 17 at a point adjacent the opening 20^b through which the jet passes.

We have found that by ionizing the mercury vapor, of which the jet is composed, it is possible to start an arc from the cathode 17 to the anode 15 almost instantaneously. That is to say, in a time period of the order of a microsecond. For this purpose we prefer to provide an igniter lead, or auxiliary electrode 27, having an intermediate portion 27^a of a metal such as tungsten which is surrounded by a glass seal 22^d formed in the peripheral wall of chamber 22, and an inner end portion 27^b which contacts with the body of mercury 17^a a substantial distance below the upper surface of the latter.

Any suitable circuit arrangement (not shown) may be provided for energizing the auxiliary electrode 27 either simultaneously with or subsequently to energization of the anode 15 and cathode 17; such means, of course, being arranged in a suitable manner to insure that the electrical potential of jet 17^d is poled right with respect to the potential of cathode 17 to insure starting of tube 10. As aforesaid both the cathode pool 17 and the mercury body 17^a are automatically reconstructed during operation of tube 10.

We have found by experiment that the ionized vapor jet starting means herein disclosed may be improved and made more reliable, in respect of insuring substantially instantaneous starting of the power tube, by causing a portion, at least, of the vapor of the jet to contact or impinge upon a body of dielectric material which is itself in contact with the mercury forming the cathode pool. Such a modification is illustrated in Figs. 4 and 5, wherein parts corresponding to those aforescribed have been given like numerals of reference. Thus, in Figs. 4 and 5, we have shown the hood 20 as provided with an approximately pear-shaped opening 20^c; and formed integrally with or fused to the narrower upper end edge thereof is a glass nib 20^d which projects outwardly and then downwardly in such a manner that the lower end 20^e penetrates, or is located below, the surface of the cathode pool 17. The exact reason for the resultant phenomenon is not known, but it is believed that the lower end 20^e of nib 20^d acts to collect and store the electrical charges of the ionized vapor particles, which discharge to the cathode in such a manner as to produce almost instantaneously an arc between the same and the surface of the mercury pool; the required potential for actual production of an arc between such elements being generated very rapidly. In Fig. 5 the dotted line 17^d indicates the normal level of the cathode pool with respect to the end 20^e of the dielectric nib 20^d.

In Fig. 6 we have shown a further modification, which is functionally similar to that shown in Figs. 4 and 5. However, in Fig. 6 the glass hood 20 is provided with a circular opening 20^f which is preferably of substantially greater area than the aforementioned opening 20^c. After formation of the opening 20^f in any suitable manner a pair of glass rods 28, about .040 inch in diameter, are laid in parallel relationship to each other, with a space of about .020 inch therebetween, across the opening 20^f. The opposite ends of rods 28 are then fused into the main body of hood 20 in a relationship to provide for vertical positioning of said rods when tube 10 is in its operative

position, as indicated in Fig. 6. The arrangement is such that the aforementioned jet 17^a is directed toward the surface of the cathode pool through the slit between rods 28, whereby contact of the jet with one or both of said rods is insured. The normal level of the cathode pool is indicated by the dotted line 17^b in Fig. 6.

In the modified form of our invention shown in Fig. 7 most of the parts illustrated may be identical with those shown in Fig. 1, and the same have been given corresponding numerals of reference. However, in Fig. 7 we employ a glass ring or annulus 29 having a notch 29^b formed in the upper edge thereof as shown through which the vapor jet (not shown) may be ejected from opening 21^a into contact with the surface of the cathode pool 17. Thus in Fig. 7 the dome-shaped upper end of the hood 20 of Fig. 1 has been omitted. The bell 21 of the boiler may be attached to ring 29 for support by the latter at, say, three equally spaced points, by positioning and fusing a small quantity or bead of glass at each point, thus forming rigid connections between ring 29 and bell 21; one of such connections being shown at 30. By eliminating the dome-shaped upper end of the hood (of Fig. 1) we minimize the possibility of collection or aggregation of the jet particles upon a dielectric surface in electrically insulated relationship to the cathode pool 17. We have found by experiment that the arrangement just described improves operating characteristics of the tube. It is to be understood, of course, that with a device like that of Fig. 7, suitable dielectric elements like those illustrated at 20^a, 20^b in Fig. 4, or at 28 in Fig. 6, may, and preferably are, provided to effect the additional improved results aforementioned.

We claim:

1. In a gridless power tube having therein an anode and a mercury pool type cathode, a long-lived make alive starter requiring less than one watt of energy on sixty cycle power, said starter including a reconstructible body of mercury normally electrically separated from the mercury of said cathode, said tube being operable without a holding arc.

2. In a gridless power tube having therein an anode and a mercury pool type cathode, a long-lived make alive starter requiring less than one watt of energy on sixty cycle power, said starter including a reconstructible mercury vapor jet electrode, the source of mercury of said vapor jet comprising a reconstructible body of liquid mercury normally electrically separated from the mercury of said cathode, said vapor jet electrode providing for operation of said tube without a holding arc.

3. In a gridless power tube having therein an anode and a mercury pool type cathode, a long-lived make alive starter requiring less than one watt of energy on sixty cycle power, said starter including a continuously operable mercury-vapor jet, the source of mercury of said vapor jet comprising a reconstructible body of liquid mercury normally electrically separated from the mercury of said cathode, and an auxiliary electrode in contact with said last mentioned body of mercury to provide for ionization of said vapor jet, said vapor jet when ionized providing for operation of said tube without a holding arc.

4. In a gridless power tube having therein an anode and a mercury pool type cathode, a long-lived make alive starter requiring less than one watt of energy on sixty cycle power, said starter

including a continuously operable mercury vapor jet, the source of mercury of said vapor jet comprising a reconstructible body of liquid mercury normally electrically separated from the mercury of said cathode, an auxiliary electrode in contact with said last mentioned body of mercury to provide for ionization of said vapor jet, said vapor jet when ionized providing for operation of said tube without a holding arc, and a refractory dielectric element itself in contact with the mercury of said cathode pool and located in the path of at least a portion of said vapor jet where the latter impinges on said cathode pool.

5. A power tube having therein an anode and a mercury pool type cathode, and means comprising a body of mercury normally electrically separated from the cathode for providing an ionized vapor jet starter for said tube.

6. A power tube having therein an anode and a mercury pool type cathode, means providing an ionized mercury vapor jet starter for said tube, said last mentioned means comprising a body of mercury electrically and mechanically separated from said cathode, heating means associated with said last mentioned body of mercury to vaporize continuously a portion of the same, and means including an auxiliary electrode for effecting ionization of said vapor jet.

7. A power tube having therein an anode and a pool type cathode, means providing an ionized vapor jet starter for said tube, said last mentioned means comprising a body of cathode material electrically and mechanically separated from said cathode, heating means associated with said body of cathode material to vaporize continuously a portion of the same, and means comprising an auxiliary electrode covered by the surface of said body of cathode material to insure ionization of the vaporized portion thereof at will.

8. A power tube having therein an anode and a pool type cathode, means providing an ionized vapor jet starter for said tube, said last mentioned means comprising a body of cathode material electrically and mechanically separated from said cathode, heating means associated with said body of cathode material to vaporize continuously a portion of the same, means comprising an auxiliary electrode covered by the surface of said body of cathode material to insure ionization of the vaporized portion thereof at will, and associated means for directing the ionized vapor in the form of a jet against the surface of said cathode to effect production of a cathode spot upon the latter.

9. In a power tube, in combination, a sealed envelope having therein an anode and a reconstructible cathode, said envelope also having therein a chamber containing a body of the material of said cathode in insulated relationship to the latter, means for heating said body of material to effect vaporization of a portion thereof continuously, means for directing the vapor so generated under relatively high pressure against the surface of said cathode, and means including an auxiliary electrode electrically connected under the surface of said body of material to provide for ionization of said vapor at will.

10. In a power tube, in combination, a sealed envelope having therein an anode and a reconstructible cathode, said envelope also having therein a chamber containing a body of the material of said cathode in insulated relationship to the latter, means for heating said body of material to effect vaporization of a portion thereof continuously, said chamber having a closed upper

end, said chamber having an opening formed in a side wall thereof to provide for overflow thereinto of the excess of cathode material, said opening also providing for passage of the vapor so generated in the form of a jet from said chamber against the surface of said cathode, and means comprising an auxiliary electrode electrically connected with said body of material beneath the surface of the latter to provide for ionization of said vapor at will.

11. In a power tube, in combination, a sealed envelope having therein an anode and a reconstructible cathode, said envelope also having therein a chamber containing a body of the material of said cathode in insulated relationship to the latter, means for heating said body of material to effect vaporization of a portion thereof continuously, said chamber having a closed upper end, said chamber having an opening formed in a side wall thereof to provide for overflow thereinto of the excess of cathode material, said opening also providing for passage of the vapor so generated in the form of a jet from said chamber against the surface of said cathode, means comprising an auxiliary electrode electrically connected with said body of material beneath the surface of the latter to provide for ionization of said vapor at will, and means comprising a dielectric element in contact with the cathode surface, said dielectric element being so positioned as to insure contact of at least a portion of said vapor jet therewith at or closely adjacent the point of impingement of said jet against said cathode surface, at least a portion of said dielectric element being in contact with said cathode.

12. In a power tube having therein an anode and a pool type cathode, the combination with means for continuously reconstructing said cathode, said means comprising a well sealed to and depending from said tube, a body of cathode material positioned within said well in electrically insulated relationship to the cathode, means providing for overflow of the excess material from said cathode to said well, means for heating the material in said well to effect continuous vaporization of a portion of the same, means for directing the vapor so formed in a relatively small stream against the surface of said cathode, and means comprising an auxiliary electrode for effecting ionization of said vapor at will to facilitate formation of a cathode spot at or adjacent the point of impact of said vapor stream against said cathode surface.

13. In a power tube having therein an anode and a pool type cathode, the combination with means for continuously reconstructing said cathode, said means comprising a well sealed to and depending from said tube, a body of cathode material positioned within said well in electrically insulated relationship to the cathode, means providing for overflow of the excess material from said cathode to said well, means for heating the material in said well to effect continuously vaporization of a portion of the same, means for directing the vapor so formed in a relatively small stream against the surface of said cathode, and means comprising an auxiliary electrode in contact with the material in said well, said electrode cooperating with said cathode through said vapor to effect ionization of the latter at will to provide for substantially instantaneous formation of a cathode spot upon said cathode.

14. A power tube having therein an anode and

a pool type cathode, means providing an ionized vapor jet starter for said tube, said last mentioned means comprising a body of cathode material electrically and mechanically separated from said cathode, heating means associated with said body of cathode material to vaporize continuously a portion of the same, means comprising an auxiliary electrode covered by the surface of said body of cathode material to insure ionization of the vaporized portion thereof at will, associated means for directing the ionized vapor in the form of a jet against the surface of said cathode to effect production of a cathode spot upon the latter, and means comprising a dielectric element in contact with said cathode and located in the path of at least a portion of said jet at or closely adjacent the point of impingement of the latter against said cathode surface.

15. In a power tube, in combination, a sealed container having therein an anode and a mercury cathode, said container also having sealed thereto and communicating therewith a chamber containing a body of mercury normally mechanically and electrically separated from said cathode, means for heating said separated body of mercury to effect vaporization of a portion thereof continuously, means for directing the vapor so generated in the form of a jet against the surface of said cathode, and an auxiliary electrode in contact with said separated body of mercury beneath the surface thereof, whereby said vapor may be ionized at will.

16. In a power tube, in combination, a sealed container having therein an anode and a mercury cathode, said container also having sealed thereto and communicating therewith a chamber containing a body of mercury normally mechanically and electrically separated from said cathode, said chamber having a closed upper end and an opening in a side wall thereof to afford the communication aforementioned, the lower portion of said opening forming a weir to provide for overflow of the excess quantity of mercury from said cathode to said chamber, means for heating said separated body of mercury to effect vaporization of a portion thereof continuously, the vapor so generated being adapted to pass in the form of a jet through the upper portion of said opening against the surface of said cathode, and an auxiliary electrode in contact with said separated body of mercury below the surface thereof, whereby said vapor may be ionized at will.

17. In a power tube having a reconstructible cathode, in combination, a chamber in said tube containing a body of the material of said cathode in normally insulated relationship to the latter, means for continuously heating said body of material to effect generation of vapor, means for directing the generated vapor in the form of a jet against the surface of said cathode, and electrical means associated with said body of material and operable under given conditions to effect ionization of said vapor, whereby initiation of conduction between said cathode and an associated anode is facilitated.

18. In a power tube, in combination, a sealed flask having therein an anode and a mercury pool cathode, said flask having a chamber sealed thereto and depending therefrom, a body of mercury partially filling said chamber and normally mechanically and electrically separated from said cathode, means providing for overflow of the excess of mercury from said cathode to said chamber, means for continuously applying a pre-

determined degree of heat to the mercury in said chamber to effect generation of vapor at a predetermined rate, means for directing the vapor so generated in the form of a jet against the surface of said cathode, and an auxiliary electrode in contact with the body of mercury in said chamber and adapted upon energization thereof jointly with said anode and cathode to effect ionization of said vapor, whereby formation of a cathode spot is facilitated.

19. In a power tube having an anode and a mercury pool type cathode, in combination, a chamber sealed to and depending from the lower end of said tube, a body of mercury partially filling said chamber and normally electrically insulated from said cathode, means providing for overflow of the excess mercury from said cathode to said chamber, a boiler located within said chamber, said boiler including a bell-shaped member the lower end of which is immersed in said body of mercury, a heating element positioned within said member and adapted to effect generation of mercury vapor continuously, said member having an opening formed therein through which said vapor is permitted to escape in the form of a jet, the arrangement being such that said jet is adapted to impinge against the surface of said cathode, and an auxiliary electrode electrically connected with said body of mercury to provide for ionization of said vapor jet at will.

20. In a power tube having an anode and a mercury pool type cathode, in combination, a chamber sealed to and depending from the lower end of said tube, a body of mercury partially filling said chamber and normally electrically insulated from said cathode, means providing for overflow of the excess mercury from said cathode to said chamber, said chamber having a reentrant recess formed therein and projecting above the surface of said mercury body, a bell-shaped member surrounding said recess and having its lower end submerged within said body of mercury, whereby a relatively small portion of the latter is accommodated within said bell-shaped member, an electric heating element positioned within said recess and adapted to effect vaporization of the mercury of said body continuously, said bell-shaped member having an opening formed in a side wall thereof to permit escape of the

generated vapor and to direct the same in the form of a jet against the surface of said cathode, and means including an auxiliary electrode located within said chamber to effect ionization of said vapor at will.

21. In a power tube having an anode and a mercury pool type cathode, in combination, a chamber sealed to and depending from the lower end of said tube, said chamber having a reentrant recess formed therein, an electric heating element positioned within said recess, a tubular insulating member extending downwardly in spaced relation to the wall of said recess throughout the major portion of the length of the latter, 10 whereby a relatively small portion of said mercury body has free access to the space between said insulating member and the wall of said recess, said insulating member having a wall portion thereof reflexed upwardly upon and in spaced 15 relation to itself from its lower end throughout the major portion of its length to minimize the transmission of heat to the main portion of said mercury body, said reflexed wall portion having a multiplicity of outwardly projecting bosses 20 formed integrally therewith to substantially center and stabilize said insulating member within said chamber, said insulating member having a downwardly angled opening formed in a side wall thereof, said heating element when energized being 25 adapted to effect vaporization of the mercury of said body continuously, the resulting vapor being directed by said opening in the form of a jet against a given spot in the cathode surface, and an electrode immersed within said body of 30 mercury and adapted when energized under given conditions to effect ionization of the vapor of said jet, whereby starting of said tube is facilitated.
